UNITED STATES PATENT OFFICE.

BERNARD F. JOHNSON, OF PAWTUCKET, RHODE ISLAND, ASSIGNOR OF
TWO-THIRDS TO WILLIAM H. PHILIPS, OF PAWTUCKET, RHODE
ISLAND, AND WILLIAM J. MCCLUE, OF PROVIDENCE, RHODE ISLAND.

SHADE-ROLLER BRACKET.

SPECIFICATION forming part of Letters Patent No. 727,802, dated May 12, 1903.

Application filed September 6, 1902. Serial No. 122,429. (No model.)

To all whom it may concern:

Be it known that I, BERNARD F. JOHNSON, a citizen of the United States, residing at the city of Pawtucket, in the county of Providence and State of Rhode Island, have invented certain new and useful Improvements in Shade-Roller Brackets, of which the following is a specification.

My invention relates to an improvement in window-brackets for shade-rollers; and the object of my invention is to produce a bracket of very simple construction and which can be readily adjusted to accommodate the device to shade-rollers of different lengths.

With this end in view the invention consists in the combination and arrangement of parts, as hereinafter described and claimed.

The invention is clearly illustrated in the accompanying drawings, in which—

Figure 1 represents a front view of the upper portion of a window-frame with a pair of my improved shade-roller brackets applied thereto and a shade-roller and shade supported between the brackets. Fig. 2 is a perspective view of the base member and provided with means for holding the bracket in position upon the same. Fig. 3 is a perspective view of the bracket member. Fig. 4 is an end view of the base secured to the window-frame and the bracket mounted in the base, and Fig. 5 is a front elevation of Fig. 4.

Like letters of reference indicate like parts in the different views of the drawings.

The invention consists of three principal parts—a base A, a slide B, and an intermediate spring C, which is secured to the base and adapted to hold the slide in any desired position upon the same. Each of these members is struck up from sheet metal.

Referring to Fig. 2, the base A has opposite longitudinal flanges b b', which provide grooves c c' on their inner sides. The lower portion of the flange b' is bent at a right angle therefrom to form an outer extension, as b². C is a flat steel bow-shaped spring, one end of which is secured to the inner side of the extension b² by a rivet d. The base A is provided with perforations e e to receive screws e' for attaching the base to the window-frame f.

Referring to Fig. 3, the slide B has a flat body portion g, having opposite rear extensions g' g', that terminate with outer longitudinal flanges g² g³, which are adapted to move freely within the grooves c c' of the base A. 55 The flange g³ is made deeper than that of the flange g², so as to have the upper rear extension g' of the slide B below the outer extension b² of the base A, and thus providing a channel h for the reception of the bow-spring 60 c in making frictional contact upon the surfaces of the said extensions g' and b² in the manner as illustrated in Fig. 5.

When not under tension, the end i of the spring C is free from contact with the extension b² of the base A, as seen in Fig. 2, so that when the slide is being mounted on the base the upper extension g' of the slide will compress the spring within the recess or channel h, and the middle portion of this spring 70 extends straight, so as to expose a large bearing-surface, as i', to engage upon the surface of the extension g' and hold the slide in any desired adjustment upon the base.

The tension of the spring C is sufficient to 75 prevent the slide from accidental disarrangement.

Projecting from the body portion g of the slide B at one end thereof is the bracket proper, g⁴, which is provided with the usual 80 opening j near its extremity to receive the pintle k of the shade-roller l.

By my construction it will be readily understood that the slides B B can be quickly adjusted to any fixed position to accommodate shade-rollers of different lengths and at the same time forming a device of this character that is very simple, durable, and inexpensive to manufacture. 85

Having described my improvement, what I 90 claim, and desire to secure by Letters Patent, is—

1. In a bracket for supporting shade-rollers, the combination, with a base adapted to be fixed against the window-frame and having 95 opposite guide-flanges, one of which flanges projects so as to form an outer extension, a slide adapted to move in the guides of said base and having a shoulder situated adjacent the aforesaid extension of the guide-flange, a 100

bracket proper carried by the said slide, and a bow-shaped spring having one end secured to the said extension of the guide-flange and its free portion arranged to engage upon the 5 said shoulder of the slide, as shown and for the purpose specified.

2. In a bracket for supporting shade-rollers, the combination, with a base adapted to be fixed against the window-frame and having 10 opposite longitudinal flanges provided with grooves on their inner sides, one of said flanges terminating with an outer extension, a slide having a flat body portion with opposite rear extensions terminating with outer longitudi-

nal flanges that move in the grooves of said 15 base, a bracket proper integral with said slide, and a bow-shaped spring rigidly secured to and adapted to bear against the outer extension of said base and to bear against a rear extension of said slide, as shown and for the 20 purpose specified.

In testimony whereof I affix my signature in presence of two witnesses.

BERNARD F. JOHNSON.
